H. C. SCHROEDER

TOILET SEAT COVER DISPENSING AND FORMING DEVICE

Filed Feb. 13, 1924

FIG.1

FIG.2

FIG.4

INVENTOR
Harry C. Schroeder

UNITED STATES PATENT OFFICE.

HARRY C. SCHROEDER, OF OAKLAND, CALIFORNIA, ASSIGNOR TO HELEN M. BERGSMA,
OF OAKLAND, CALIFORNIA.

TOILET-SEAT-COVER DISPENSING AND FORMING DEVICE.

Application filed February 13, 1924. Serial No. 692,450.

To all whom it may concern:

Be it known that I, HARRY C. SCHROEDER, a citizen of the United States, residing at Oakland, in the county of Alameda and 5 State of California, have invented certain new and useful Improvements in Toilet-Seat-Cover Dispensing and Forming Devices, of which the following is a specification.

10 My invention is an improved toilet seat cover dispensing and forming device.

The object of my invention is to provide a device of the above mentioned character, which will form a seat cover from the usual 15 type of rolled toilet paper.

Another object is to provide a device of this character which is simple in construction and inexpensive to manufacture.

In the annexed drawing in which my invention is illustrated:

Figure 1 is a plan view of my machine.

Figure 2 is a sectional view taken on line 2—2 of Fig. 1.

Figure 3 is a front elevation of the same.

25 Figure 4 is a plan view of the completed cover.

Referring more particularly to the drawing, my device is mounted in a U-shaped frame 1, which is adapted to be secured to 30 the wall at a point convenient for use. A roll of paper 2 is journaled in the frame 1 at the rear thereof. Feed rolls 3 and 4 are journaled in the frame 1 forwardly of the paper 2, and are corrugated or rubber covered to better grip the paper.

35 A pair of conical forming rolls 5 and 6 are journaled in the frame 1 forwardly of the rollers 3 and 4, in which the paper is given a circular shape. The paper feeds 40 through the large end of the conical rollers faster than at the small end. The paper is fed into the forming rolls at a speed which conforms with the large end. Thus the lag at the small end causes the paper to crease 45 and forms a ring as shown at 7 which is torn from the roll on the knife 8 and is placed upon the toilet seat.

The rolls 5 and 6 are geared together by gears 9 and 10, and are rotated by a handle

11 secured to the shaft of the roller 5. A 50 gear 12 secured to the roller 5 meshes with an idler gear 13 which in turn meshes with a gear 14 secured to the roller 3. The rolls 3 and 4 are geared together by gears 15—15 secured thereto. It will be seen that the rotation of the crank 11 causes the rolls 5, 6, 3 and 4 to rotate and feed the paper from the roll 2 into the circular shape shown in Figure 4.

Having described my invention, I claim:

1. A toilet seat cover dispenser comprising a frame, a roll of paper journaled in said frame, a pair of conical rollers mounted forwardly of said paper roll, and means to rotate said conical rollers.

2. A toilet seat cover dispenser comprising a frame, a roll of paper journaled in said frame, a pair of conical rollers mounted forwardly of said paper roll, a crank secured to one of said rolls, and gears secured 65 to each of said rolls and adapted to mesh.

3. A toilet seat cover dispenser comprising a frame, a roll of paper journaled in said frame, a pair of conical rollers mounted forwardly of said paper roll, means to rotate said conical rollers, and a pair of feed rolls mounted between said paper roll and said conical rolls.

4. A toilet seat cover dispenser comprising a frame, a roll of paper journaled in 80 said frame, a pair of conical rollers mounted forwardly of said paper roll, means to rotate said conical rollers, a pair of feed rolls mounted between said paper roll and said conical rolls, a gear secured to one of said 85 conical rolls, an idler gear meshing therewith, and a gear secured to one of said feed rolls meshing with said idler gear.

5. A toilet seat cover dispenser comprising a frame, a roll of paper journaled in 90 said frame, a pair of conical rollers mounted forwardly of said paper roll, means to rotate said conical rollers, a pair of feed rolls mounted between said paper roll and said conical rolls, and means to drive said feed 95 rollers.

In testimony whereof I affix my signature.

HARRY C. SCHROEDER.
